[57] CLAIM

The ornamental design for my modular flower stand and trellis combination, as shown and described.

DESCRIPTION

FIG. 1 is a front perspective view of a modular flower stand showing my new design;

FIG. 2 is a rear perspective view thereof;

FIG. 3 is a front perspective view of a second embodiment of the design of FIG. 1;

FIG. 4 is a rear perspective view of FIG. 3;

FIG. 5 is a perspective view of a third embodiment of the design of FIG. 1 showing the modules in an associated arrangement.

FIG. I

FIG. 2
